UNITED STATES PATENT OFFICE.

OLE BERGERSON, OF BIG LAKE, MINNESOTA.

BELT-GUIDE.

1,086,885.

Specification of Letters Patent.

Patented Feb. 10, 1914.

Application filed August 8, 1912. Serial No. 714,001.

To all whom it may concern:

Be it known that I, OLE BERGERSON, a citizen of the United States, residing at Big Lake, in the county of Sherburne and 5 State of Minnesota, have invented certain new and useful Improvements in Belt-Guides; and I do hereby declare the following to be a full, clear, and exact description of the invention, such as will enable others 10 skilled in the art to which it appertains to make and use the same.

My invention has for its object to provide an improved belt guide and supporting device, adapted for general use, but especially 15 adapted for use in connection with traction engines; and, to the above ends, the invention consists of the novel devices and combinations of devices, hereinafter described and defined in the claim.

20 The invention is illustrated in the accompanying drawings, wherein like characters indicate like parts throughout the several views.

Referring to the drawings, Figure 1 is a 25 view showing the improved device in end elevation and applied in working position to a portion of a traction engine and, by means of dotted lines, the improved device is shown as the same would appear when 30 turned into an inoperative position; Fig. 2 is a view partly in side elevation and partly in vertical section, taken on the line x^2-x^2 of Fig. 1, on an enlarged scale; Fig. 3 is a plan view of the parts shown in Fig. 2, 35 some parts being broken away and with some of the exposed parts shown in section; and Fig. 4 is a detail view in vertical section, taken on the line x^4-x^4 of Fig. 2.

Of the traction engine illustrated for the 40 purpose of showing the improved device applied in working position, the numeral 1 indicates a portion of the boiler and the numeral 2 indicates the driving pulley over which runs a belt 3.

45 Referring to the improved belt guide and supporting device, the numeral 4 indicates an L-shaped supporting bracket. The vertical member of this bracket 4 is bent to conform to the shape of the shell of the 50 boiler 1, as shown in Fig. 2, and is detachably secured thereto at its intermediate portion by a nutted bolt 5, and at its upper end by a nut-equipped eye-bolt 6. By reference to Fig. 1, it will be noted that the supporting bracket 4 is attached to the boiler 1 close 55 to the pulley 2, at a point that is easily ac-

cessible from within the boiler 1 outward of the adjacent ends of the boiler flues, not shown.

Pivottally mounted on the horizontal member of the supporting bracket 4, is a yoke-like supporting frame 7, arranged to embrace the lower section of the belt 3. The prongs 8 of this supporting frame extend one above the other and horizontally outward from the boiler 1 and they also extend transversely of the belt 3. Integrally formed with the lower and upper corners of the supporting frame 7, is, respectively, a hinge lug 9 and an anchor bracket 10. The hinge lug 9 extends horizontally away from the lower prongs 8 and forms a continuation thereof. And the anchor lugs 10 extend vertically upward from the intermediate portion of the supporting frame 7 and forms a continuation thereof. The hinge lug 9 rests upon the horizontal member of the supporting bracket 4, and is pivottally secured thereto by a nutted bolt 11.

Pivottally secured to the upper end of the pivot bolt 11 is an upwardly and outwardly projecting brace rod 12. The upper end of the rod 12 is passed through a hole in the anchor lug 10 and is rigidly secured thereto by a pair of opposing clamping nuts 13 having screw threaded engagement with the brace rod 12. In addition to the pivot bolt 11, the supporting frame 7 is further anchored to the supporting bracket 4 by a long horizontally extended eye-bolt 14, connected to the eye-bolt 6 by a link 15 passed through the eyes of the said bolts. The threaded end of the eye-bolt 14 is passed through a hole in the anchor lug 10 above the brace rod 12, and is anchored thereto by 95 a pair of opposing clamping nuts 16. As shown in Fig. 2, the connection between the eye-bolt 14 and the link 15 is vertically aligned with the pivot bolt 11, thereby permitting free lateral swinging of the improved device.

Adjustably mounted between the prongs 8 of the supporting frame 7 and extending in the same vertical plane therewith, is a horizontally extended supporting roller 17 over 105 which runs the lower section of the belt 3. This belt supporting roller 17 is loosely journaled on the intermediate portion of a yoke-like rod 18, the depending prongs of which are passed loosely through a pair of holes 19 in the lower prong 8 of the supporting frame. Having screw threaded engage-

ment with each of the prongs of the rod 18, is a pair of opposing adjusting nuts 20, adapted to engage the opposite faces of the lower prong 8. Coöperating with each of the lower nuts 20 is a lock nut 21. Obviously, by adjusting the nuts 20, the prongs of the rod 18 may be raised or lowered, at will, thereby changing the angularity of the belt supporting roller 17 with respect to the prongs 8 of the supporting frame 7. By adjustably mounting the roller 17 with respect to the supporting frame 7, the said roller may be adjusted so as to keep the same in a substantially horizontal position, irrespective of the position of the support to which it is attached.

A pair of vertically extended guiding rollers 22 and 23 are mounted between the prongs 8 of the supporting frame 7, and are located, one at each end of the belt supporting roller 17 in positions to engage the edges of the belt 3 and thereby guide the same as it travels over the roller 17. The belt guiding roller 22 is loosely journaled on a vertically extended nut-equipped bolt 24, passed through the two prongs 8 close to the vertical or intermediate member of the supporting frame 7; and the belt guiding roller 23 is loosely journaled on a vertically extended eye-bolt 25. At its outer end, the lower prong 8 of the supporting frame 7 is bifurcated and the outer end portion of the upper prong 8 thereof is provided with a side notch 26. The eye end of the bolt 25 is pivotally secured between the prongs of the bifurcated end of the lower bar 8 by a pivot pin 27. The upper or free end of the bolt 25 is adapted to be inserted in the notch 26 by a lateral movement thereof. Having screw threaded engagement with the upper end of the eye-bolt 25, is a clamping nut 28 adapted to be turned into engagement with the upper prong 8, and frictionally hold the bolt 25 interlocked therewith.

To further lock the eye-bolt 25 and the roller 23 carried thereby, in operative positions, a flange-equipped lock plate 29 is pivotally secured at 30 to the upper prong 8. In the intermediate portion of the lock plate

29, is punched or cut a hole 31 through which 50 the free end of the eye-bolt 25 projects when said lock plate is turned down, as shown by full lines in Fig. 2. In this position of the lock plate 29, its flanges embrace the ends of the prong 8 and thereby hold the said lock 55 plate properly positioned.

To remove the improved device from the belt 3, the lock plate 29 is first turned upward into an inoperative position. The clamping nut 28 is then released and the eye-bolt 25 removed from the notch 26 and, together with the roller 23, is turned downward on the pivot pin 27. In this position of the roller 23, the improved device is free to be swung laterally into a position parallel 65 to the boiler 1 and entirely free from the belt 3. To positively lock the improved device, either in an operative or an inoperative position, the hinge lug 9 is provided with a lateral extension, in which is formed a pin 70 seat 33 adapted to register with either one of a pair of pin seats 34 formed in the horizontal member of the supporting bracket 4. Through the pin seat 33 and through either one of the pin seats 34, a headed lock pin 32 75 is adapted to be passed. The pin seats 34 are located substantially at right angles to each other, thereby holding the device in either of its two extreme positions.

What I claim is:—

The combination with a supporting frame having a pair of horizontal, vertically spaced prongs, of a pair of vertical, laterally spaced belt guiding rollers journaled on said prongs, the journals of the outer belt 85 guiding roller permitting swinging movement of said roller to and from operative positions, a horizontal belt supporting roller journaled between said belt guiding rollers, and means securing the ends of the journal 90 for said belt supporting roller to one of said prongs for independent vertical adjustment.

In testimony whereof I affix my signature in presence of two witnesses.

OLE BERGERSON.
